UNITED STATES PATENT OFFICE.

GEORGE HOGAN, OF NEW BRIGHTON, NEW YORK.

INDICATOR FOR SCHOOLS.

SPECIFICATION forming part of Letters Patent No. 276,819, dated May 1, 1883.

Application filed August 10, 1882. (No model.)

To all whom it may concern:

Be it known that I, GEORGE HOGAN, a citizen of the United States, residing at New Brighton, Richmond county, New York, have 5 invented new and useful Improvements in Indicators for Schools, of which the following is a specification.

This invention relates to devices for recording and displaying the grade or meritorious standing of the respective scholars in a school, and for other similar purposes; and it consists in the combination of a series of dovetailed name-receiving slides, with a panel having its face provided with horizontal grooves for the 10 reception of the slides, and with a vertical marking strip or column adjacent to one end of the grooves, so that when the slides are inserted in the grooves they are firmly held in position and are capable of being interchanged at pleasure, 15 while the marking-strip is a medium common to all the slides for containing the grades of the scholars. One end of the grooves is closed to arrest the slides and bring them to the proper symmetrical positions. Opposite to the 20 grooves on the face of the panel, and at the end opposite to the grade-marking strip, are consecutive numbers for denoting the numerical standing of the scholars, while on the upper part of the panel is a marking-strip designed 25 to receive a date, such strip being arranged in proper relation to a suitable inscription on the panel, as hereinafter more fully set forth.

This invention is illustrated in the accompanying drawings.

35 Figure 1 is a face view, showing some of the slides partially drawn out to expose the grooves. Fig. 2 is a vertical section on the line $x x$, Fig. 1; and Fig. 3 is a broken sectional view through a portion of the panel and some of the slides.

40 Similar letters indicate corresponding parts.

The letter A designates the name-receiving slides; B, the panel; C, its grooves; D, the grade-marking strip, and E the date-marking strip.

45 The slides A are dovetailed in cross-section, and hence are firmly retained in position, due to their shapes, and the desired names are printed on the slides; or, in lieu thereof, a facing of slate or the like may be used for temporarily receiving the names. Each slide, more-

over, is provided with a finger-button, f, to facilitate its adjustment.

The panel B is composed of wood, cardboard, or other stiff material, and it is inclosed in a frame, B'; but, if desired, this frame may 55 be omitted.

The grooves C extend in horizontal planes side by side with each other, and they are formed by means of strips C', which are dovetailed and secured to the face of the panel B 60 in the proper manner to receive the slides A between them. Next to one end of the grooves C the panel B is provided with a cleat, g, for closing such end of the grooves, the other end being left open, and hence when the slides are 65 inserted in the grooves they are arrested by the cleat, thus taking the proper symmetrical positions.

The grade-marking strip D is situated at or adjacent to one end of the grooves C—namely, 70 the open end—and it extends vertically the entire height or aggregate width of the grooves, so that it is common to all the slides. It is preferred to make this strip D of slate or other similar material, and to sink the same into the 75 panel B, flush with its face, as shown in Fig. 2. At or adjacent to the closed end of the grooves C the face of the panel B is marked with consecutive numbers, one opposite to each groove, as shown in Fig. 1, and hence the numerical 80 standing of the scholars can be indicated, as well as the grades.

The date-marking strip E is arranged on the upper part of the panel B, in proper relation to an inscription denoting the week or other 85 period to which the whole appertains or is made to apply, and it is preferably made, like the strip D, of an argillaceous material sunken into the panel.

What I claim as new, and desire to secure by 90 Letters Patent, is—

1. A device for receiving and displaying the grade or standing of scholars in a school, consisting of a panel having its face provided with a series of horizontal parallel dovetailed 95 grooves, a series of removable name-receiving slides having dovetailed upper and lower edges, and a grade-marking strip secured vertically to the panel at one end of the dovetailed grooves, substantially as described.

2. The combination, substantially as herein-before set forth, of the removable dovetailed name-receiving slides, with the panel having its face provided with a series of horizontal parallel grooves for the reception of the slides, closed at one end, but open at the other end, and with a vertical grade-marking strip at one end of the grooves.
3. The combination, substantially as herein-before set forth, of the removable dovetailed name-receiving slides, with the panel having its face provided with a series of horizontal parallel grooves for the reception of the slides, with a vertical grade-marking strip at one end of the grooves, and with consecutive numbers at the other end thereof, such numbers being opposite to the grooves.

4. The combination, substantially as herein-before set forth, of the removable dovetailed name-receiving slides, with the panel having its face provided with a series of horizontal parallel grooves for the reception of the slides, with a vertical grade-marking strip at one end of the grooves, and with a date-marking strip, the latter being arranged in proper relation to the inscription on the panel.

In testimony whereof I have hereunto set my hand in the presence of two subscribing witnesses.

GEORGE HOGAN.
